UNITED STATES PATENT OFFICE.

EDWARD A. RIX, OF OAKLAND, CALIFORNIA.

FLUID-COMPRESSOR.

1,264,562.

Specification of Letters Patent. Patented Apr. 30, 1918.

Application filed December 20, 1915. Serial No. 67,771.

To all whom it may concern:

Be it known that I, EDWARD A. RIX, a citizen of the United States, residing at Oakland, in the county of Alameda and State of California, have invented new and useful Improvements in Fluid-Compressors, of which the following is a specification.

This invention relates to fluid compressors.

10 No air or gas compressor delivers from its cylinders an amount of fluid equal to the displacement of the piston. The ratio between these quantities determines the volumetric efficiency of the compressor. The 15 average industrial compressor gives from 40% to 75% volumetric efficiency.

The object of my invention is to correct this deficiency in an inexpensive and effective manner so that a compressor may under 20 ordinary conditions deliver a much larger amount.

This object I accomplish by providing in a fluid compressor a main and an auxiliary compression chamber or cylinder such that 25 the contents of the auxiliary chamber, compressed on the intake stroke of the piston, will be flashed into the main cylinder at or near the beginning of the return stroke of said piston, whereby to secure a partial or 30 initiatory compression in the main cylinder prior to the regular compression stroke of the piston therein.

One form which my invention may assume is exemplified in the following description and illustrated in the accompanying drawing, in which—

Figure 1 shows a longitudinal, central sectional view of a device embodying my invention.

40 Fig. 2 shows a similar view of the same, illustrating the piston in a different position and disclosing a slight modification in the arrangement of the parts.

Referring in detail to the form of my invention illustrated herewith, I have shown 45 a compressor cylinder 10, containing a double piston 11, and having a head 12 provided with the usual inlet valve 13 and discharge valve 14. These valves and the cylinder construction may be of any number or 50 of any type. The piston may be reciprocated in any manner, but is shown as being propelled by a piston rod 15.

The lower part of the cylinder and piston

is smaller than the upper part, thus leaving 55 a small compression chamber 16 opposite the main compression chamber 17. A pocket 18, at the side of the cylinder, communicates, through a port 19, with said chamber 16 and forms therewith an auxiliary compression 60 chamber. A flashing port 20, uncovered by the piston at the lower end of its travel, connects said pocket with the main chamber and a similar port 21, opening to the atmosphere and uncovered at the upper end of the 65 piston travel, communicates with the chamber 16.

For the best practical results I prefer to make the cubic contents of the chamber 16 and pocket 19, when fully opened, each 70 equal to one-third of the cubic contents of the main chamber 17, but any desired ratio may be taken, depending upon the conditions.

The operation of the device described is 75 as follows: If the piston 11 in its upper position, as shown in Fig. 2, is made to descend, the fluid will be drawn through the inlet valve 13 and will continue to fill the chamber 17 until the stroke is finished. At 80 the same time the air in the auxiliary compression chamber will be compressed, and at the end of the stroke, with the ratio given above, the fluid will be compressed to fifteen pounds per square inch. When the 85 descending piston uncovers the port 20 the fluid in the auxiliary chamber, now under pressure, will flash into the chamber 17 and tend to equalize the pressures in all, which, with the above ratio, will result in about 90 four pounds gage pressure. The upward stroke then beginning will discharge the augmented contents of the chamber 17 through the discharge valve 14 and into the receiver. At the end of the discharge stroke 95 the flash port 21 is uncovered to the chamber 16 and atmospheric air will be sucked quickly in, owing to the partial vacuum in said chamber.

With the before mentioned ratios, and 100 measured with a meter, the fluid delivered will be equal to 100% of the full capacity of the chamber 17 at sixty pounds pressure, and 93% of its capacity at one hundred pounds pressure; an increase of 30% over 105 the capacity of a compressor without my compensating arrangement. Actual measurement of the power consumed, with elec-

trical instruments, showed that the 30% in-crease of volume required but 15% increase of power.

One of the principal causes of inefficiency in the ordinary puppet valve compressors is the late complete closing of the inlet valves at the beginning of the compression stroke. To correct this trouble by heavier springs is only to make another; namely, a too early closing. With my device, when the flash port 20 opens the rush of incoming air closes the inlet valves instantly, and weak springs or no springs may be used.

A clear difference in principle is to be noted between the present operation and that of a two-stage compressor. If the cycle of operation is analyzed it will be seen that a two-stage compressor as such compresses all of its output in two stages and all work done on the contents of the cylinders is done by the pistons, while in my device only the augmented portion of the fluid goes through two stages of compression. The flash from the pocket 19 through port 20 into the main chamber compresses the entire contents of the latter to a considerable degree instantly and without any mechanical intervention. Moreover, in expanding from the higher pressure in the auxiliary chamber to the lower pressure in chamber 17, the air cools and absorbs the heat of the flash compression, thus making it isothermal, or nearly so, which is a most economical condition. This feature differs from the two-stage in that no intercooler is used or desired, because I wish to preserve the heat of compression in the auxiliary chamber and cause it to return its power by expansion work in the main cylinder.

In a four-cycle gas engine the cylinder is alternately an explosive power cylinder and then an air and gas compressor. It is well known that at high altitudes the power of a gas engine decreases because the weight of air compressed is less and consequently the oxygen necessary to consume the hydro-carbon is less, but with my compensating construction this deficiency can be completely remedied by making an auxiliary cylinder operating in the manner hereinbefore described furnish an additional amount to offset the maximum altitude loss and regulate the amount the auxiliary cylinder will deliver for all intermediate altitudes by simply using a throttling valve. An aviator may then be free from the dangerous vagaries which now attend his motor at high altitudes. This device may be attached to either a single or double acting, horizontal or vertical compressor.

There will be a partial vacuum in the auxiliary chamber after the upward stroke has progressed beyond the point where the compressed fluid therein has expanded to

atmosphere, this vacuum will be destroyed by the opening of the flash port 21. However, there need be no vacuum at all if it is desired to prevent loss of power for a check valve 22 may be placed on the auxiliary 70 chamber to allow air to enter whenever it is needed.

The flash ports need not necessarily be placed in the cylinder. The flash port 21 may be done away with entirely and check 75 valve 22 used instead, or both may be used. For the flash port 19 a valved port may be substituted.

It is manifest that various changes may be made in details of construction without departing from the principle of the invention, which is the arrangement, in conjunction with the regular compression chamber of a compressor, of means to give an augmented charge or initial partial compression at or adjacent to the beginning of the compressing stroke of the piston, and while the drawing illustrates one embodiment of the invention the claims define the scope of the same.

Having thus described my invention, what I claim and desire to secure by Letters Patent is—

1. A fluid compressor comprising in combination, a cylinder, and a piston in said cylinder dividing the same into a main compression chamber and an auxiliary compression chamber, said auxiliary compression chamber having less area than the main chamber and said piston being operable during the major portion of the extension stroke to compress fluid in the auxiliary chamber and discharge the same into the main chamber only at or near the beginning of the compression stroke.

2. A fluid compressor comprising in combination a cylinder and piston forming a main compression chamber and an auxiliary compression chamber of less area than the main chamber and independent of the inclosure for the piston actuating means, said auxiliary chamber being arranged to have its contents compressed during the major portion of the extension stroke of the piston in the main chamber, and communicating means between said chambers whereby the compressed fluid in the auxiliary chamber is flashed into the main chamber only at or near the beginning of the compression stroke of the piston therein.

3. A fluid compressor comprising in combination a cylinder and piston forming a main compression chamber and an auxiliary compression chamber of less area than the main chamber and independent of the inclosure for the piston actuating means, said auxiliary chamber being arranged to have its contents compressed during the major portion of the extension stroke of the piston in the main chamber, communicating means

between said chambers controlled by the piston and adapted to be opened only when the piston is at or near the beginning of its compression stroke in the main chamber whereby to initially raise the pressure of the fluid in the latter chamber, and means communicating with the atmosphere and the auxiliary chamber controlled by said piston and adapted to be opened at or near the beginning of the extension stroke of the piston in the main chamber.

4. In a fluid compressor, the combination of a cylinder, a differential piston therein forming therewith a main and an auxiliary chamber, inlet and outlet ports for said main chamber, an inlet port for said auxiliary chamber controlled by the piston and adapted to be opened at or near the beginning of the extension movement of said piston in the main chamber, and communicating means between said chambers controlled by the piston and adapted to be opened when the piston is at or near the beginning of its compression stroke in the main chamber, whereby to initially raise the pressure of the fluid in the latter chamber.

5. In a fluid compressor, the combination of a cylinder, a differential piston therein forming therewith a main and an auxiliary chamber, a pocket in the side of said cylinder forming a part of said auxiliary chamber, inlet and outlet ports for said main chamber, an inlet port for said auxiliary chamber controlled by the piston and adapted to be opened at or near the beginning of the extension movement of said piston in the main chamber, and communicating means between said chambers controlled by the piston and adapted to be opened when the piston is at or near the beginning of its compression stroke in the main chamber, whereby to initially raise the pressure of the fluid in the latter chamber.

6. In a fluid compressor, the combination of a cylinder having a main compression chamber at one end and an auxiliary compression chamber formed intermediate the ends of the cylinder, a piston common to both of said chambers and operable to compress fluid in the auxiliary chamber during the major portion of its extension movement and discharge the fluid into the main chamber only at or near the beginning of its compression stroke in the latter chamber.

55. 7. In a fluid compressor, the combination of a cylinder and piston forming a main and auxiliary compression chamber, said cylinder having its inner end open to the atmosphere and the piston acting to segregate the auxiliary chamber from the open end of the cylinder, said auxiliary chamber being arranged to have its contents compressed during the major portion of the extension stroke of the piston of the main chamber, and communicating means between said

chambers whereby the compressed fluid in the auxiliary chamber is flashed into the main chamber only at or near the beginning of the compression stroke of the piston in the latter.

8. In a fluid compressor, the combination of a cylinder having an enlarged closed end and a reduced open end, a differential piston working in said cylinder and forming a main and auxiliary compression chamber in the enlarged end, whereby the contents of the auxiliary chamber is compressed during the major portion of the extension stroke of the piston in the main chamber and discharged into the latter only at or near the beginning of the compression stroke of the piston in the main chamber.

9. A fluid compressor including in combination a cylinder composed of an upper main chamber and a lower auxiliary chamber of less area than the main chamber, a differential piston having upper and lower portions fitting the main and auxiliary chambers, inlet and outlet ports for the main chamber, an inlet port for the auxiliary chamber controlled by the upper portion of the piston and adapted to be opened at or near the beginning of the extension movement of the piston in the main chamber, and communicating means between said chambers controlled by the piston and adapted to be opened only when the piston is at or near the beginning of its compression stroke in the main chamber whereby to initially raise the pressure of the fluid in the latter chamber.

10. A fluid compressor including in combination a cylinder composed of an upper main chamber and a lower auxiliary chamber of less area than the main chamber, a differential piston having upper and lower portions fitting the main and auxiliary chambers, inlet and outlet ports for the main chamber, a pocket in the side of said cylinder forming part of the auxiliary chamber, an inlet port for the auxiliary chamber controlled by the upper portion of the piston and adapted to be opened at or near the beginning of the extension movement of the piston in the main chamber, and communicating means between said chambers controlled by the piston and adapted to be opened only when the piston is at or near the beginning of its compression stroke in the main chamber whereby to initially raise the pressure of the fluid in the latter chamber.

11. A fluid compressor including in combination a cylinder composed of an upper main chamber and a lower auxiliary chamber of less area than the main chamber, a differential piston having upper and lower portions fitting the main and auxiliary chambers, inlet and outlet ports for the main chamber, a pocket in the side of said cylinder,

der forming part of the auxiliary chamber, an inlet port for the auxiliary chamber controlled by the upper portion of the piston and adapted to be opened at or near the beginning of the extension movement of the piston in the main chamber, an inlet port at the lower end of the pocket leading into the latter from the auxiliary chamber and a flashing port at the upper end of the pocket, said inlet and flashing ports of the pocket constituting communicating means between said chambers controlled by the

piston and adapted to be opened only when the piston is at or near the beginning of its compression stroke in the main chamber ¹⁵ whereby to initially raise the pressure of the fluid in the latter chamber.

In testimony whereof I have hereunto set my hand in the presence of two subscribing witnesses.
